UNITED STATES PATENT OFFICE

126,093

DESIGN FOR A HEAT RETAINING NURSING BOTTLE HOLDER

Charles N. Lockwood, Chicago, Ill.

Application October 16, 1940, Serial No. 95,874

Term of patent 7 years

To all whom it may concern:

Be it known that I, Charles N. Lockwood, a citizen of the United States of America, residing at Chicago, in the county of Cook, State of Illinois, have invented a new, original, and ornamental Design for a Heat Retaining Nursing Bottle Holder, of which the following is a specification, reference being had to the accompanying drawing, forming a part thereof.

Fig. 1 is a front elevational view of my heat retaining nursing bottle holder, showing my new design; Fig. 2 is an exploded front elevational view showing the cover removed from the container; Fig. 3 is an enlarged front view of the decoration appearing on the front of the container.

The characterizing feature of my design resides in the nursing bottle holder shown, having an oval-like ornamental panel on the side thereof specifically as shown.

I claim:

The ornamental design for a heat retaining nursing bottle holder, substantially as shown and described.

CHARLES N. LOCKWOOD.
